CLAIM

The ornamental design for an LED wall light, as shown and described.

DESCRIPTION

FIG. 1 is a perspective view of an LED wall light, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view of portion of FIG. 1 thereof. The broken lines shown in the drawings illustrate portions of the LED wall light that form no part of the claimed design.
